UNITED STATES PATENT OFFICE.

HENRY PERCY HOWLETT, OF STOKE-UPON-TRENT, ENGLAND, ASSIGNOR TO HERMAN C. KUPPER, INC., OF NEW YORK, N. Y., A CORPORATION OF NEW YORK.

DESIGN FOR A PLATE OR SIMILAR ARTICLE.

Application filed March 8, 1927, Serial No. 21,065. Term of patent 7 years.

To all whom it may concern:

Be it known that I, HENRY PERCY HOWLETT, a subject of the King of Great Britain and Ireland, residing at Stoke-upon-Trent, county of Stafford, England, have invented a new, original, and ornamental Design for a Plate or Similar Article, of which the following is a specification, reference being had to the accompanying drawing, forming part thereof.

I claim:

The ornamental design for a plate or similar article, as shown.

HENRY PERCY HOWLETT.
